UNITED STATES PATENT OFFICE.

WILLIAM W. SLOANE, OF CHICAGO, ILLINOIS, ASSIGNOR TO GOODMAN MANUFACTURING COMPANY, OF CHICAGO, ILLINOIS, A CORPORATION OF ILLINOIS.

LOCOMOTIVE.

Application filed July 25, 1921. Serial No. 487,376.

To all whom it may concern:

Be it known that I, WILLIAM W. SLOANE, a citizen of the United States, residing at Chicago, in the county of Cook and State of Illinois, have invented an Improvement in 5 Locomotives, of which the following is a specification.

This invention relates to improvements in locomotives or trucks and has for its principal object to provide an improved construction affording relative flexibility of the supporting wheels and axles so as to readily follow uneven track.

A usual type of construction of locomotives comprises a plurality of axles with supporting wheels thereon, said axles journaled in suitable axis boxes mounted in vertically disposed guides carried by the locomotive frame and having springs interposed 10 between each axle box and the frame. Such a construction allows the ends of an axle to move vertically a limited distance, depending upon the resiliency of the springs, thereby affording limiting flexibility of movement of opposite ends of the axle.

In the present invention I provide transversely movable means affording greater flexibility of movement of the axle, comprising an equalizing device in which the 15 opposite ends of an axle have a pair of bell crank levers interposed between them and the frame. The bell crank levers are operatively connected with each other, so as to allow the axle to swing in a vertical plane 20 independent of the resiliency of the springs.

This invention consists in the combination, construction and arrangement of parts as will hereinafter be described in connection with the accompanying drawings and more 25 particularly defined in the appended claims.

Figure 1 is a fragmentary top plan view of one type of locomotive constructed in accordance with my invention.

Figure 2 is a vertical cross section taken 30 on line 2—2 of Figure 1 with a portion of a supporting wheel broken away to show the mounting for one end of the axle.

Figure 3 is an enlarged transverse cross section taken on line 3—3 of Figure 1.

Figure 4 is a view similar to Figure 2 showing an alternative form of my invention.

Figure 5 is a vertical cross section taken 40 on line 5—5 of Figure 4.

Figure 6 is a side view illustrating the 55 manner of applying my improved construction to a two-axle locomotive.

Figure 7 is a side view of a three-axle locomotive, illustrating another application of 60 my invention.

Figure 8 is a side view of a four-axle locomotive illustrating a third manner in which my invention may be applied.

In the drawings, a simple embodiment of 65 my invention is shown as applied to the locomotive shown in Figure 6. A portion of this locomotive is shown in Figures 1, 2 and 3, in which appear two side plates 2, 2, constituting the main portion of the frame, an axle 3, and a pair of supporting wheels 4, 4, 70 thereon. A motor casing 5 is suspended on the axle 3 to provide motive power therefor, said motor casing being journaled at one end on the shaft 3 and flexibly connected near the other end to the locomotive frame 75 in any manner suitable to electric locomotives of the type illustrated. Each end of the axle 3 is journaled in a journal box 6 of any approved construction, said journal box being arranged to move vertically between 80 pedestals, or guide plates 7, 7 of the usual construction.

Referring now more particularly to the 85 novel features constituting my invention, the locomotive frame is supported on the journal boxes 6, 6 through the medium of an equalizing device constructed as follows: In the embodiment of my invention illustrated in Figures 1, 2 and 3, a pair of rocking members 8, 8 are mounted on the locomotive frame above their respective axle boxes. Each of said rocking members comprises, in effect, a bell crank lever pivotally 90 mounted to swing in a vertical plane transversely of the locomotive.

In the form illustrated, said rocking member has two bearing pins 9, 9, on a common longitudinal axis and pivotally mounted in brackets 10, 10, carried on the side plate 2 of the locomotive frame. Said pins form 100 the fixed axis of movement of the rocking member and are connected together by a longitudinally extending member 11. One lever arm of the rocking member comprises an arm 12, (see Figures 2 and 3) connected 105 to the longitudinal member 11 and arranged to one side of the axis of pivot pins 9, 9. Said member 12 bears on a stirrup 13, which

carries a pair of springs 14, 14, interposed between said stirrup and the axle box 6. The lower end 15 of the member 11 is preferably arcuate in cross-section, as shown in Figure 3, to fit in a corresponding depression 15 formed in the upper surface of said stirrup. The parts are retained in place by a pair of pins 16, 16, extending through opposite ends of the stirrup, and into recesses in the arm 12 as shown.

The second lever arm of the rocking member 8 comprises an inwardly extending member 17, arranged above the axis of said rocking member and pivotally connected with a transverse equalizing bar 18, extending across the locomotive and attached to a similar rocking arm above the opposite end of the axle 3.

In applying my invention to a locomotive of the two-axle type shown in Figure 6, one supporting axle 3^a is preferably mounted in the usual manner, that is to say, without an equalizing device, so as to provide a desired stability to the frame, while the other supporting axle is mounted as above described, so as to afford a wide range of flexibility with respect to the frame and the one stabilizing axle connected therewith as described. By means of this arrangement, the locomotive wheels may readily follow uneven track.

Among other forms in which my invention may be embodied, I have illustrated a modification in Figures 4 and 5, which is particularly adapted for use in instances where the overall height of the locomotive is limited, as for instance, in a mine locomotive. In this construction, the longitudinally extending member 11^a, corresponding with the member 11 in the preferred construction, is lengthened considerably to accommodate the supporting wheel 4^a, the upper flange of which extends vertically above the axis of the supporting pivots 9^a, 9^a, as clearly shown in Figure 5. Also, the cross-bar 17^a is positioned near one end of the longitudinal member 11^a. In other respects the construction and operation is similar to the form already described.

In the form illustrated in Figure 7 my invention is shown as applied to a three-axle locomotive having a pair of equalizer bars 30, 30 of the usual type at each side of the frame. Each equalizer bar extends from the center axle-box to an end axle-box and has a suitable set of springs 31 interposed between said bar and the locomotive frame. In order to provide transverse equalization with my device, the springs 31 at one end of the frame are cross-connected by an equalizing device similar to that shown in Figures 1, 2 and 3. Another application of my device is shown in Figure 8 which shows a four-axle locomotive in which the axles are grouped in pairs, each pair having lon-

gitudinally extending equalizer bars 32, 32 and supporting springs 33, 33. In this construction, the springs 33, 33 supporting one pair of axles are cross-connected through the medium of an equalizing device in a manner similar to that shown in Figures 6 and 7. By means of the arrangements shown, the axles are equalized as to transverse movement as well as longitudinal movement.

Having described my invention what I claim as new and desire to cover by Letters Patent is:

1. In a car, a frame, an axle having supporting wheels, and an equalizing device comprising a pair of rocking members, each pivotally mounted on opposite sides of the frame and affording a vertically movable support for one end of said axle, and horizontally movable means connecting said rocking members together.

2. In a car, a frame, an axle having supporting wheels, journal boxes adjacent the ends of said axle, guide means on said frame permitting limited vertical movement of said journal boxes, and an equalizing device comprising two bell crank levers, each pivotally mounted on the frame and having a laterally disposed arm in supporting relation with one journal box and a substantially vertical arm, and means operatively connecting said vertical arms together.

3. In a car, a frame, a pair of laterally spaced axles, one of said axles being provided with a transverse equalizing device comprising a pair of rocking members each pivotally mounted on opposite sides of the frame, and affording a vertically movable support for one end of said equalized axle, and horizontally movable means connecting said rocking members together.

4. In a car, a frame, an axle having supporting wheels, and a pair of rocking members, each having two pivot pins mounted on the frame and spaced laterally on opposite sides of a supporting wheel, and a connecting member integral with said pivot pins and offset laterally to accommodate said wheel, a bearing member carried by said connecting member in supporting relation with the adjacent end of the axle, an upwardly extending arm also carried by said connecting member, and a bar connecting said upwardly extending arms on each of said rocking members.

5. In a car, a frame, three laterally spaced axles having supporting wheels, two pairs of longitudinally disposed equalizer bars, each pair connecting the center axle with one of the other axles, the pair of bars at one end of the frame being provided with a transverse equalizing device comprising two rocking members, each pivotally mounted on opposite sides of the frame and affording a vertically movable support for one

of said equalizer bars, and horizontally movable means connecting said rocking members together.

6. In a car, a frame, two pairs of axles 5 having supporting wheels, each of said pairs of axles being connected by longitudinally disposed equalizer bars at each side of the frame, the pair of bars at one end of the frame being provided with a transverse 10 equalizing device comprising two rocking members, each pivotally mounted on opposite sides of the frame and affording a vertically movable support for one of said equalizer bars, and horizontally movable means 15 connecting said rocking members together.

7. In a car, a frame, an axle, supporting means on opposite ends of said axle movable vertically with respect to said frame, a pair of rocking members at opposite sides 20 of the frame and interposed between said supporting means and said frame, and transversely movable means operatively connecting said rocking members together.

8. In a car, a frame, a pair of supporting 25 axles, one of which is provided with an equalizing device comprising a pair of rocking members each interposed between said frame and one end of said axle to afford relative vertical movement therebetween, 30 and transversely movable means operatively

connecting said rocking members together.

9. In a car, a frame, three laterally spaced axles having supporting wheels, two pairs of longitudinally disposed equalizer bars, each pair connecting the center axle with 35 one of the other axles, the pair of bars at one end of the frame being provided with a transverse equalizing device comprising two rocking members, each interposed between one of said bars and the frame, and 40 affording vertical movement between said bar and frame, and horizontally movable means connecting said rocking members together.

10. In a car, a frame, two pairs of axles 45 having supporting wheels, each of said pairs of axles being connected by longitudinally disposed equalizer bars at each side of the frame, the pair of bars at one end of the frame being provided with a transverse 50 equalizing device comprising two rocking members, each interposed between one of said bars and the frame, and affording vertical movement between said bar and frame, and 55 horizontally movable means connecting said rocking members together.

Signed at Chicago, Illinois, this 23rd day of July, 1921.

WILLIAM W. SLOANE.
